CELLOPHANE COVERED STEEL WIRE

Sol D. Cohen, New York, N. Y.

Application October 20, 1939, Serial No. 300,381

4 Claims. (Cl. 41—10)

The invention relates to a steel wire to be used particularly in conjunction with the fabrication of ornamental devices, such as garlands, wreaths, etc., in which there are utilized foliated strips of regenerated cellulose to constitute the body of the ornamental structure. A comparatively recent improvement in this art has been the impregnation or treatment otherwise of the regenerated cellulose with a fire-retarding chemical composition. This improvement has been necessitated by the conventional use of such garlands and wreaths as ornaments in the decoration of a Christmas tree, with its attendant fire hazards, especially when the decorative devices are placed in juxtaposition to a lighted candle or even an incandescent bulb emitting a degree of heat sufficient, in certain circumstances, to ignite the ordinary regenerated cellulose or Cellophane, which will immediately burst into flame.

The types of chemical compositions now used to render the Cellophane utilized for these purposes, flame-resistant, are such as are described in patents to Cupery 2,142,115 and 2,142,116 in which patents there are disclosed certain types of fire-retarding compositions, particularly aqueous or dispersions of sulfamic acid or the salts thereof. In accordance with the disclosures of such patents, non-fibrous cellulosic structures impregnated with sulfamic acid or the salts thereof, show a decreased tendency to ignite and burn. They are, therefore, considered as flame-resistant.

The use of this type of flame-resistant chemical impregnated Cellophane in the fabrication of Christmas tree garlands and wreaths has, I have found, given rise to a serious problem. Decorative devices like wreaths and garlands, are ordinarily fabricated by twisting or winding Cellophane sheets in foliated condition upon one or more steel wires, which are themselves twisted to clamp between them, the strips of Cellophane. Such steel wires, in addition to being subject to corrosion by atmospheric influences, for instance, the ordinary quantity of moisture present in air, become corroded by reason of the contact therewith of the chemicals which have been used to impregnate the Cellophane, forming the body of the garland or wreath. This corrosive action is undoubtedly due to the breaking down of the chemicals constituting the fire-retardant material, and within a very short time, the steel wire evidences corrosion which is not only detrimental to the appearance of the ornament, but seriously affects the flexibility and springiness or twisting capacity of the wire. Furthermore, an ordinary

corrosion of such wire produces iron oxide, a powder, the surface corrosion of the wire results in the production of pulverized material which further detracts from the appearance of the ornament, especially as the powder becomes deposited upon the Cellophane, and destroys its shimmery, light-reflecting character and interferes with the uniformity of its coloring.

Especially in connection with Christmas tree ornaments which are desired to have a certain degree of flexibility, for instance, garlands which are to be utilized in the decoration of a Christmas tree by being draped through and upon branches thereof by the consumer, is this problem of corrosion a troublesome one. With each flexing of the steel wire, constituting the core of the garland, a certain amount of pulverized rust is scaled from the wire. Furthermore, the original degree of flexibility, springiness and twisting capacity of the wire must necessarily be retained in order to make possible a draping of the garland in the decoration of the Christmas tree in any manner that the tree decorator may see fit.

I have discovered that this problem of maintaining the appearance of the ornament and retaining the original flexibility, springiness, and twisting capacity, is due entirely to the corrosive influence upon the wire of the ingredients of the compound or chemicals used in impregnating the Cellophane to render it fire-retardant or flame-resistant.

A solution of this problem resides in providing the steel wire with a coating of a moisture-proof material, sufficiently flexible in itself to be wound or otherwise applied to the steel wire, which is customarily of small gauge, so as to provide a barrier to the contact of the impregnated chemicals, or any salts or reductive products thereof, with the surface of the steel wire. As the fire-retardant chemicals are ordinarily impregnated in the form of an aqueous solution or dispersion, a moisture-proof covering layer, such as regenerated cellulose itself, is an ideal barrier. In accordance with my invention, therefore, I provide for the protection of the steel wire from the corrosive influences of the chemical or chemicals used to provide the fire-retardant effect to the Cellophane, a covering layer or plurality of covering layers constituted of a sheet or sheets of Cellophane wound or twisted, in convoluted fashion upon and throughout the steel wire. This covering layer or layers will then constitute a moisture-proof insulating material between the

steel wire and the chemically impregnated Cellophane.

In this manner, the chemical reaction, i. e., resulting in corrosion of the steel wire, between the impregnating chemicals and the steel wire, will be completely prevented, so that there will be no destruction of the original qualities of the steel with respect to its flexibility, springiness, and twisting capacity.

10 It will be noted that by this extremely simple expedient, i. e. the provision of a single or multiple layer of a moisture-proof material upon the steel wire, the destructive effect of the chemically impregnated Cellophane upon the 15 steel wire is totally eliminated, while at the same time permitting the twisting or other type of working of the steel wire, either in the production of the ornament or thereafter, which working may occur many months subsequent to 20 the original fabrication of an ornament such as a garland.

A specific embodiment of my invention is illustrated in the accompanying drawing in which Fig. 1 is an elevational view of a strip of wire having a wrapping of regenerated cellulose; Fig. 2 is an elevational view of an ornament, in the form of a garland, made in accordance with my invention, in which each of two twisted wires is enwrapped with a strip of regenerated cellulose, and the wires and enwrapment are in turn used as a support for a foliated strip of regenerated cellulose impregnated with fire-retarding chemicals; Fig. 3 is a plan view of a Christmas tree wreath in the fabrication of which my invention has been embodied; and Fig. 4 is a cross-section of a wire and wrapping of regenerated cellulose as shown in Fig. 1.

Referring more particularly to the drawing, in which similar reference characters identify similar parts in the several views, 5 is a steel wire with a strip 6 of regenerated cellulose wrapped around it. In forming the ornament of Fig. 2, the core of the ornament comprising two twisted steel wires 7 and 8, each wrapped in strips of regenerated cellulose 9 (Cellophane), there is clamped between said wires a regenerated cellulose strip 10 impregnated with fire-retarding chemicals, the strip 10 being foliated, by being gathered up into folds.

50 In Fig. 3 I have illustrated the ornament as constituting a Christmas tree wreath, which comprises a core of two twisted steel wires 7 and 8, a wrapping 9 of regenerated cellulose about each of the wires, the foliated, fire-retarding, 55 chemically impregnated, regenerated cellulose strip 10 being clamped between the wires at spaced intervals.

In the fabrication of a wreath of the general type described, it is conventional to use two steel wires intertwined, clamping between them the sheets of Cellophane previously treated with the fire-retarding chemical, and by further twisting of the Cellophane sheets, producing the foliated condition by which the wreath is formed.

60 65 I am aware that it has been heretofore suggested to utilize, as an insulating layer of materials other than a steel wire, a cellulose material, even regenerated cellulose, but in every such instance, the insulation has been used for

electric conductors and the insulating quality or effect has been produced by the combination of a layer of a cellulosic material and rubber or similar material. In every such instance, also, the conductor sought to be insulated, for instance, from sulphur or chlorine compounds in the outer layer, has been copper wire or some other suitable electrical conductor. It has been hereinabove pointed out, that my invention relates specifically to the problem relating to, and 10 arising from, the use of a steel wire in which it is necessary to retain a degree of flexibility and twisting capacity. Furthermore, I know by actual experience that the particular chemicals capable of being used for impregnating, for purposes of fire-retardation, regenerated cellulose, have a destructive and deteriorating or corrosive influence upon the steel hereinabove set forth, whereas they do not have the same destructive effect upon copper. It will be recognized by 20 those skilled in the art that a steel wire, constituted primarily of iron, is subject to corrosion by certain chemicals which may not have the same destructive effect upon other metals and certainly the steel wire will be attacked and affected to a much greater degree and in much less time, than would be a wire constituted of some other metal or even alloy.

I claim:

1. The combination, with a chemically active 30 corrosive impregnated regenerated cellulose body, of a steel wire, said steel wire being covered throughout its outer surface, by a convoluted strip of regenerated cellulose acting as a barrier to the penetration of the corrosive to the steel 35 wire.

2. A decorative ornament comprising a steel wire, a wrapping of regenerated cellulose throughout the length of said wire and in direct contact therewith, a regenerated cellulose strip, 40 impregnated with fire-retarding chemicals, said impregnated regenerated cellulose strip being entwined about said steel wire, said wrapping of regenerated cellulose serving as a barrier to prevent the influence of the fire-retarding chemicals penetrating to the steel wire.

3. A decorative ornament comprising a core of two twisted steel wires, a wrapping of regenerated cellulose about each of said wires, a regenerated cellulose strip impregnated with fire- 50 retarding chemicals clamped between said wires and regenerated cellulose wrapping at spaced intervals; and foliated to form the body of the ornament, said wrapping of regenerated cellulose about each of said steel wires serving to protect 55 the steel wire from the corrosive action of the fire-retarding chemicals with which the foliated regenerated cellulose strip is impregnated.

4. A decorative ornament comprising a steel wire, a wrapping of regenerated cellulose 60 throughout the length of said wire and in direct contact therewith, a regenerated cellulose strip, impregnated with fire-retarding chemicals, said impregnated regenerated cellulose strip being supported upon, and by, said steel wire, said 65 wrapping of regenerated cellulose serving as a barrier to prevent the influence of the fire-retarding chemicals penetrating to the steel wire.

SOL D. COHEN.
